UNITED STATES PATENT OFFICE

137,653

DESIGN FOR A TOY TRACTOR

James P. Donahue, Oak Park, Ill.

Application February 2, 1944, Serial No. 112,411

Term of patent 14 years

(Cl. D34—15)

To all whom it may concern:

Be it known that I, James P. Donahue, a citizen of the United States, residing at Oak Park, in the county of Cook and State of Illinois, have invented a new, original, and ornamental Design for a Toy Tractor, of which the following is a specification, reference being had to the accompanying drawing, forming a part thereof.

showing my new design.

Fig. 2 is a front end view.

Fig. 3 is a side elevational view.

Fig. 4 is a plan view.

Fig. 5 is a rear end view.

I claim:

The ornamental design for a toy tractor, substantially as shown.

JAMES P. DONAHUE.
